UNITED STATES PATENT OFFICE.

GEORGE W. COON, OF NEW YORK, N. Y.

DESIGN FOR A TOP.

SPECIFICATION forming part of Design No. 22,378, dated May 2, 1893.

Application filed March 13, 1893. Serial No. 465,828. Term of patent 7 years.

To all whom it may concern:

Be it known that I, GEORGE W. COON, a citizen of the United States, residing in the city, county, and State of New York, have invented a new and original Design for Tops, of which the following is a specification, reference being had to the accompanying drawings, in which—

Figure 1 is a sectional view of the top showing my design. Fig. 2 is an elevation, and Fig. 3 is a plan view of the same.

The leading feature of my design is the shield shaped configuration or outline of the top. The sides *a a* diverge in curved outline upwardly from the base of the top, then curve inwardly in outline at *b b*. The upper

portion *c c* converges in outline toward the top, and the top curves downwardly in outline at *d d*, and the central portion *e* rises in a form of circular knob or button. The surfaces of the top are divided by lines disposed vertically and forming stripes, and the portions *b c d* are ornamented with stars.

What I claim is—

The design for a top, substantially as shown and described.

Signed by me this 10th day of March, A. D. 1893.

GEORGE W. COON.
